UNITED STATES PATENT OFFICE.

ARTHUR W. McCALLISTER, OF BAIRD, OKLAHOMA.

WORKING BARREL FOR WELLS.

Application filed January 19, 1922. Serial No. 520,416.

To all whom it may concern:

Be it known that I, ARTHUR W. McCALLISTER, a citizen of the United States, residing at Baird, in the county of Cotton and 5 State of Oklahoma, have invented certain new and useful Improvements in Working Barrels for Wells, of which the following is a specification.

This invention relates to pumps for deep 10 wells, such as oil wells, and the primary object of this invention is the provision of novel means for insuring the correct operation of the pump by preventing the settling of sand or other foreign matter on the 15 valves, which would tend to clog said valves, and thus prevent the free operation thereof. In deep well pumps considerable difficulty has been experienced with sand getting into the working barrel and clogging up the 20 standing and working valves, often necessitating the pulling of the valves and the cleaning out of the working barrel. Considerable experimenting has been done in order to prevent the sand from getting into 25 the working barrels and certain sand traps have been designed, which have not been found to be satisfactory in use.

It is therefore a prime object of the invention to provide a novel working barrel 30 for pumps and a novel arrangement of valves therefor, whereby the collecting of sand in the barrel and on the valves and seats will absolutely be precluded, the valves and working barrel being so constructed as 35 to permit the fluid passing therethrough to wash and keep the valves in a cleanly condition.

Another object of the invention is the provision of a working barrel for fitting directly within the pump casing and spaced 40 therefrom, and having valves disposed in the working barrel for forcing the liquid first into the lower portion of the working 45 barrel and then out between the working barrel and casing into the ordinary casing pipe.

A further object of the invention is the provision of novel means for preventing the falling of sand or other débris into the 50 working barrel of the pump as the fluid is forced up into the well casing pipe, and to provide a novel means for preventing the collecting of sand at the lower end of the working barrel, ports being disposed therein 55 in such a manner as to permit the sand to be washed out from the lower end of the work-

ing barrel and into the space intermediate the working barrel and the well pump casing.

A still further object of the invention is 60 to provide a novel device for preventing the collecting of sand or other foreign matter around the standing and working valves of pumps of the above character, which will be durable and efficient in use, one that will be 65 simple and easy to manufacture, and one which can be associated with the pump casing at a low cost.

With these and other objects in view, the invention consists in the novel construction, 70 arrangement and formation of parts, as will be hereinafter more specifically described, claimed and illustrated in the accompanying drawings, forming a part of this specification, in which drawings:

Figure 1 is a vertical longitudinal section through a well pump casing and working barrel thereof, showing the standing valve and the working plunger or piston in elevation.

Figure 2 is an enlarged longitudinal sectional view through the well pump casing, barrel and standing valve and operating plunger, showing the plunger in its lowermost position.

Figure 3 is a similar view showing the working or operating plunger in a raised position and illustrating the position of the inlet and outlet valves when the plunger is in its raised position.

Figure 4 is a detail transverse section taken on the line 4-4 of Figure 3, illustrating the manner of connecting the air escape valve to the working or operating plunger gland.

Figure 5 is a detail section taken on the line 5-5 of Figure 3 showing the air escape or pressure port.

Figure 6 is an enlarged detail transverse section taken on the line 6-6 of Figure 3, 100 illustrating the fluid escape ports in the standing valve.

Figure 7 is an enlarged detail transverse section taken on the line 7-7 of Figure 3.

Figure 8 is an enlarged detail transverse 105 section taken on the line 8-8 of Figure 3.

Referring to the drawings in detail, wherein similar reference characters designate corresponding parts throughout the several views, the letter A indicates a well 110 pump casing; B, a working barrel; C, the standing or stationary portion of the pump;

D, the operating or working portion of the pump; E, the means for preventing the settling of the sand or other débris into the working barrel at the upper end thereof; 5 and F, the means for permitting the escape of pressure through the working barrel on the up stroke of the working or operating plunger.

The well casing A consists of the usual 10 number of pipe lengths, which can be connected together in the ordinary manner. A section 11 is interposed between certain of the pipe lengths for the reception of the working barrel and this section 11 has its 15 upper and lower ends contracted as at 12 and 13. The contracted portion 13 forms a seat for the standing portion or valves of the pump and a seat for the working barrel B as will be hereinafter more fully apparent 20 as the description proceeds.

The working barrel B consists of a cylindrical tube 15 which is entirely independent 25 of the section 11, and has a diameter less than that of the section 11, in order to form a chamber 16, between the section 11 and the working barrel. The tube 15 is preferably formed in sections to facilitate the assembly 30 of the parts of the pump and includes the upper section or gland section 15', the intermediate section 16' and the lower section 17'. These sections are threaded to certain 35 stationary portions of the pump as will be hereinafter described. The upper end of the barrel B extends through a guide plate 17, which can be formed of any suitable rigid material, and this plate can be held in position in the section 11 in any preferred manner.

By way of example, the same has been 40 shown held in position against displacement by setting the same between upper and lower portions 18 and 19 of the section 11. These portions 18 and 19 can be connected together by suitable collar 20. This plate 17 45 is provided at spaced points with openings 21, which establish communication between the chamber 16 and the upper portion of the section 11 and form escape ports for the fluid being pumped.

50 The standing portion of the pump consists of a central suction tube 25, which has a novel packing gland 26 associated therewith for establishing intimate contact between the same and the contracted end 13 55 of the casing A.

This packing gland comprises a sleeve 27 fitted upon said suction pipe 25. The lower end of the sleeve is provided with an enlarged head 28, in which is threaded a nut 29. The upper end of the sleeve 27 is provided with exterior threads and threaded into a plug 30, which is in turn threaded into engagement with the lower end of the working barrel B. Confined between the 65 plug 30 and the head 28 formed upon the

sleeve 27 are a plurality of packing washers or rings 31, which are adapted to intimately engage the inner surface of the contracted end 13 of the casing A and forms a tight seat for the barrel on the casing so as to prevent accidental movement of the barrel and the seeping of fluid past the barrel and casing. The upper end of the suction pipe 25 extends through the plug 32. This plug is exteriorly threaded and connects the sections 16' and 17' of the barrel B together. 70 This plug 32 is provided with an annular row of spaced ports 33, through which the fluid is adapted to flow as will be hereinafter more fully apparent. The lower face of this 75 plug 32 is provided with an annular valve seat 34, on which is adapted to normally rest the outlet valve 35. This valve 35 has an annular raised portion 36, which is adapted to snugly fit within the annular seat 34 80 formed in the plug. The valve 35 is slidably mounted upon the suction tube 25 and is provided with the hollow cylindrical sleeve 37, around which is coiled an expansion spring 38. The terminals of the expansion spring engage respectively the upper surface of the plug 30 and the lower surface of the valve 35 and normally holds the valve 35 in a raised position on its seat 34. 85

The upper end of the suction tube 25 extends slightly above the plug 32 and is provided with a valve seat 39 for the reception of a ball valve 40, which forms the inlet valve. A suitable cage 41 may be carried by the valve seat in order to prevent accidental 90 displacement of this valve from operative position off of its seat. The barrel B directly above the plug 30 is provided with suitable outlet ports 42 as clearly shown in 95 Figures 2 and 3 of the drawings. 105

The plunger or operating portion D of the pump comprises the suction or operating rod 50, the lower edge of which has secured thereto the suction head or piston 51. This suction head or piston 51 consists of body 110 52 preferably formed of rubber packing or the like, and this body is confined between a pair of metal discs 53 and 54. The lower end of the rod has threaded thereon a nut 55, against which bears an expansion spring 115 56. This expansion spring has its lower end bearing against the disc 54 and normally tends to hold the same in contact with the body 52. The upper surface of the disc 53 has bearing against the same an adjusting 120 nut 57, which is threaded on a threaded portion 58 of the rod 50. It can be seen by adjusting the nut 57 that the body 52 can be moved into intimate contact with the inner surface of the working barrel B. The rod 125 50 extends through a suitable packing gland 60, which is supported by a plug 61. This plug 61 connects the upper section 15' and the intermediate section 16' together.

The base 62 of the gland 60 is threaded in. 130

to contact with the plug 61 and has a suitable packing 63 placed therein for engagement with the plunger rod 50. The gland follower 64 is slidably mounted in the gland base and has engaging the same the lower end of the expansion spring 65, which is coiled around the rod. The upper end of the spring bears against the gland cap 66, which is threaded in engagement with the gland base 62. The gland cap 66 supports a felt washer 67, which engages the inner surface of the upper end of the section or gland protector 15', and covers the opening 68 therein through which the plunger rod 50 extends and absolutely precludes the falling of sand or other débris within the working barrel.

The means F for relieving pressure within the working barrel between the plunger 52 and the rod 61, consists of an escape port 70 formed in the plug 61. This escape port is normally closed by a valve 71, which is held on its seat within the port by means of an expansion spring 72. The valve and expansion spring are carried by an arm 73, which is secured in any preferred manner, such as by a collar 75 with the gland base 62. In the initial starting of the pump, the air confined between the plunger and plug will be forced above the plug 50 and thus create a partial vacuum between the plunger and plug, which will facilitate the operation of the plunger due to the fact that the plunger will not have to operate against a head of air.

In operation of the improved device, upon the up stroke of the plunger or piston 52, the inlet valve 40 will be moved off of its seat 39, and a suction will be caused within the pipe 25, sucking the fluid therethrough and into the working barrel B above the plug 32. During this operation, the outlet valve 35 will be held upon its seat. During the raising movement of the plunger, the air confined between the plunger and the plug 61 if any, will be permitted to escape, owing to the fact that the pressure will lift the valve 71 from off of its seat. Upon the down stroke of the piston or plunger 52, the valve 40 will be forced on its seat, while the outlet valve 35 will be moved off its seat, thus permitting the escape of the fluid through the ports 33 into the lower end of the working barrel below the plug 32 through the outlet ports 42 formed in the barrel and then through the escape ports 21 formed within the plate 17 and then on up into the pump casing.

By this construction, it can be seen that if any sand is drawn up with the fluid through the suction pipe 25, the fluid will carry the same away from the valve seat 39 and the fluid will carry the same through the ports 33 and around the valve 35. In order to further permit the carrying off of any sand around the valve 35 and prevent the

adhering of sand around the same inclined ports 80 are formed directly in the valve and thus it can be seen that the sand will drop therethrough, and be washed and be carried through these ports. If any sand is carried up with the fluid through the chamber 16, and through the ports 21, it will be prevented from flowing back into the barrel owing to the felt washer 67 engaging the dome shaped head of the gland protector or section 15'.

From the foregoing description, it can be seen that an improved and simple means has been provided for rendering a pump positive in operation and for absolutely precluding sanding up of the valves and working barrel.

Changes in details may be made without departing from the spirit or scope of this invention; but,

I claim:

1. In a well pump, a casing, a barrel disposed in the casing in spaced relation thereto forming a chamber between the barrel and casing, means for establishing fluid tight connection between the lower end of the barrel and casing, an inlet pipe extending into the barrel and establishing communication between the barrel below the means for establishing fluid tight connection between the barrel and casing, an inlet valve for controlling the flow of fluid through the pipe, a body having ports therein fitted around said pipe in fluid tight engagement with the barrel, escape ports formed in the barrel below the body and establishing communication between the barrel and the chamber between the casing and barrel, a valve for controlling flow of fluid through said body, and a plunger reciprocably mounted within said barrel.

2. In a well pump, a casing, a working barrel disposed in the casing and arranged in spaced relation thereto forming a chamber intermediate the casing and barrel, an operating plunger in said barrel, means for preventing the entrance of fluid and foreign matter into said barrel above the plunger, a lower stationary member fitted in said barrel, means for establishing fluid tight connection between said member and the casing, a suction pipe carried by and terminating above said member, an inlet valve carried by the upper end of the suction pipe, an outlet valve carried by the member and disposed below the inlet valve and above said means for establishing fluid tight connection between the casing and member, and outlet ports formed in the barrel above said means for establishing fluid tight connection between the member and casing and communicating with the chamber intermediate the casing and working valve.

3. In a well pump, a casing, a working barrel disposed in the casing and arranged

in spaced relation thereto forming a chamber around said barrel, means for establishing connection between the lower end of the barrel and the casing, means for preventing the entrance of foreign matter in the barrel at the upper end thereof, a plunger disposed in said barrel below said last mentioned means, a member fitted within the barrel, means for establishing fluid tight connection between the lower end of the barrel and casing, means for permitting the flow of liquid through said member into the barrel above said member, an inlet valve for controlling the flow of fluid through said means, an outlet valve carried by said member and arranged below the inlet valve and above said means for establishing fluid tight connection between the casing and barrel, and means for permitting the flow of fluid 20 from the barrel below said outlet valve into the chamber through said barrel.

4. In a well pumping apparatus, a casing having a working barrel seat formed on the lower end thereof, a working barrel fitted 25 within the casing and arranged on said seat, the barrel having a smaller diameter than the casing and arranged in spaced relation to the casing to form a chamber around the same; a working plunger in said 30 barrel, means for preventing the entrance of fluid and foreign matter into said barrel above said plunger, a stationary member disposed in said barrel at the lower end thereof, means for permitting the flow of fluid 35 through said member into said barrel, inlet and outlet valves carried by said member, fluid escape ports formed within the barrel below said valves and communicating with the chamber, and means for permitting the escape of pressure within said barrel above said plunger.

5. In a well pumping apparatus, a casing having a barrel seat formed therein, a barrel having a smaller diameter than said casing 45 disposed therein and fitted on said seat and arranged in spaced relation to the casing, an operating plunger in said barrel, means for preventing the entrance of fluid and foreign matter into the barrel above said plunger, a rod carried by the plunger, means for preventing the seeping of fluid around said plunger and into said barrel, means disposed in the barrel above said plunger for permitting the escape of air above said 55 plunger during the operation thereof, a stationary member carried by the lower end of the barrel arranged in fluid tight connection therewith, inlet and outlet valves carried by said member, and outlet ports formed 60 in the barrel below said inlet and outlet valves establishing communication with the barrel and the space intermediate the barrel and casing, the said ports being arranged above the lower end of said barrel.

6. In a well pumping apparatus, a casing

having a barrel seat formed therein, a barrel having a smaller diameter than the seat fitted therein and resting upon said seat, a plunger reciprocably mounted within said barrel, means for preventing the entrance of fluid and foreign matter in the barrel above said plunger, a suction pipe extending into the lower end of the barrel, means fitted around the suction pipe for establishing fluid tight connection between the suction pipe and the lower end of said barrel, an inlet valve carried by the upper end of the suction pipe, an outlet valve fitted around the suction pipe, outlet ports formed in the barrel below said outlet valve, the ports being arranged above the lower end of the barrel, and resilient means for normally maintaining the outlet valve in its raised operative position.

7. In a well pumping apparatus, a casing having a barrel seat formed therein, a barrel having a smaller diameter than the casing fitted concentrically within the casing and disposed upon said seat, a plunger reciprocably mounted in the barrel, means for preventing the flow of fluid and foreign matter into the barrel above said plunger, a suction pipe disposed in concentric relation to the lower end of the barrel, a packing gland disposed around the suction pipe and engaging the casing to prevent the flow of fluid past the barrel and suction tube, a valve seat disposed about the suction pipe adjacent to the upper end thereof engaging said barrel, the seat having a plurality of ports extending therethrough, an inlet valve carried by the upper end of the suction pipe and disposed above the mentioned valve seat, an outlet valve slidably mounted upon the suction pipe, means normally maintaining the valve on its seat, the valve having ways formed therein for permitting the passage of fluid therethrough when the valve is forced off its seat, and escape ports formed in the valve below said outlet valve and above the lower end of the barrel and said barrel seat.

8. In a well pumping apparatus, a well casing having a working barrel seat formed therein, a working barrel having a smaller diameter than the casing disposed in concentric relation to the casing, a member fitted in the lower end of the barrel in fluid tight connection therewith and resting upon said barrel seat, inlet and outlet valves carried by said member, means for establishing communication between the barrel and the space between the barrel and the casing below the inlet valve, a plug fitted within the barrel above said plunger, a packing gland carried by said plug, a plunger rod connected to the plunger and extending through said packing gland, an air escape formed in said plug, and a spring pressed valve for controlling the flow of fluid through said port.

9. In an oil well pumping apparatus having a working barrel seat formed therein, a working barrel having a smaller diameter than the casing fitted in said casing in spaced relation thereto, a plunger reciprocably mounted in said barrel, a plunger rod connected to the plunger, a guide plate for the upper end of the barrel engaging the casing, the barrel having an opening therein for the 10 reception of the plunger rod, a plug disposed in the barrel above said plunger, a packing gland carried by the plug and disposed about said rod, a felt washer disposed about the rod and the upper end of the packing gland 15 for engaging the inner face of the upper end of said barrel to prevent the flow of foreign matter into the barrel above said plunger, an air escape port formed in said plug, a spring pressed valve carried by the packing gland for normally fitting in said port, a 20 member carried by the lower end of the barrel and arranged in fluid tight connection therewith, inlet and outlet valves carried by the member, means for permitting the flow of fluid through said member, and ports 25 formed in the barrel below the valves and establishing connection between the barrel and the space intermediate the barrel and the casing, said ports being arranged above the lower end of the barrel.

ARTHUR W. McCALLISTER.
